[57] CLAIM

The ornamental design for a combined bag distending and holding form, as shown and described.

DESCRIPTION

FIG. 1 is a perspective view of a combined bag distending and holding form showing my new design;

FIG. 2 is a top plan view thereof, the bottom view being a mirror image thereof;

FIG. 3 is a front elevational view thereof;

FIG. 4 is a rear elevational view thereof;

FIG. 5 is a left side elevational view thereof, the right side elevational view being a mirror image thereof; and

FIG. 6 is a front perspective view thereof in the position of use, the bag being shown in broken lines for illustrative purposes only.

FIG. 1

FIG. 2

FIG. 3

FIG. 4

FIG. 5

FIG. 6
